RUG NOZZLE

Arnold H. Beede, Stamford, Conn., assignor to
 Electrolux Corporation, Old Greenwich, Conn.,
 a corporation of Delaware

Application March 6, 1945, Serial No. 581,228

3 Claims. (Cl. 15—364)

1

This invention relates to rug cleaning nozzles for vacuum cleaners and is particularly concerned with nozzles having means for agitating the pile fabric of a rug or floor covering so as to provide for an enhanced cleaning action.

In the cleaning of rugs by suction means two individual problems are usually present. One of such problems is the removal of deep dirt usually in the form of dust and fine particles which is frequently lodged at the base of the piles of the rug and which can usually be best dislodged and carried into the suction stream by an agitation of the pile bristles of the rug by which they are bent over and separated from adjacent bristles, permitting the suction action to be effective deep down in the rug pile. A second problem is the removal of surface litter such as hairs and fibrous material which frequently is enmeshed with the bristles of the rug and which frequently require a surface agitation of the rug by a brush or comb which disentangles such litter, permitting it to be sucked up into the air stream.

It is among the objects of the present invention to provide a single rug nozzle which is designed to subject the rug to both a deep dirt removing action as well as a surface litter removing action.

It is a further object of the present invention to provide a rug nozzle which on the forward stroke thereof over the rug will subject the rug to one type of cleaning action while the reverse movement of the nozzle over the rug will subject the rug to a different type of cleaning action. It will, of course, be understood that the different types of cleaning are not necessarily mutually exclusive and while one or the other type of cleaning may be predominantly effective during one stroke of the nozzle some cleaning of the other type may be simultaneously taking place.

Another object of the present invention is to provide a rug nozzle having a suction opening, the width of which may be varied so as to selectively subject the rug to the action of a wide suction opening or to the action of a narrow opening which later induces a high velocity of air passing from the rug surface to the nozzle.

A still further object of the invention is to provide a rug cleaning nozzle having a pivoted agitator carrying member which is freely swingable in response to the direction of movement of the nozzle over the rug and which by such swinging movement selectively applies one or another agitating means to the rug surface.

Numerous other objects of the present invention will be apparent from a consideration of the following specification taken in conjunction with the accompanying drawings, in which:

Fig. 1 is a top plan view of a rug nozzle formed in accordance with the present invention;

2

Fig. 2 is a bottom plan view showing the nozzle with the parts in the position shown in Fig. 3;

Fig. 3 is a vertical section taken on lines 3—3 of Fig. 1 and showing the parts of the nozzle in the position assumed when the nozzle is being moved rearwardly over the rug, and

Fig. 4 is a similar view with the parts shown in the position which they assume when the nozzle is pushed forwardly over the rug.

10 The present inventive concept is herein illustrated as embodied in a suction nozzle, the suction opening of which is defined by the front wall of the nozzle body and a pivotally mounted element carrying a pair of independent variously characterized agitating elements, the arrangement being such that on the forward stroke of the nozzle the pivoted member swings rearwardly to present a wide suction opening to the rug and also to present to the rug surface a comb like agitator which is designed to pick up and disentangle from the pile of the rug fibrous surface litter such as hairs and threads. The pivoted member also carries a different type of agitator which is moved into rug contacting 20 position by pivotal movement of the member upon the rearward stroke of the nozzle. The second mentioned agitator is preferably in the form of means for flexing the pile of the rug so as to permit the suction to penetrate to the base of the pile. In the latter position of the pivoted member the lower edge has moved forwardly towards the front lip of the nozzle body to thereby reduce the width of the nozzle suction opening so that high velocity air is brought in close 30 contact with the pile of the rug.

Referring now in detail to the accompanying drawings, a preferred embodiment of the present inventive concept is disclosed as comprising a hollow suction nozzle body 10 which conveniently 40 may be of conventional elongated rectangular outline. A wand or suction handle receiving coupling, as indicated at 11, is mounted upon the body 10, it being understood that a hollow suction handle or wand may be applied to the 45 coupling 11 so that such handle or wand may function as an operating handle and as a means for applying suction to the nozzle.

The ends of the body 10 are extended rearwardly as at 12 from the front lip 13 of the body so as to constitute end enclosures or transverse walls which also act as supporting runners to assist in maintaining the nozzle opening 14 parallel with the rug surface. The opening 14 is bounded on the front side by the front 50 55 lip 13 of the nozzle body and on the ends by the end members or transverse walls 12, while the rear wall of the suction opening is defined by a pivotally mounted wall portion or agitator carrying member 15. The extreme upper edge of member 15 forms the fulcrum for pivotally

mounting member 15, the same being secured to the end walls 12 by suitable pins 16 as indicated by dotted lines of Figs. 3 and 4.

An upper seal for the pivotally mounted member 15 is provided by a flexible member or wall 17 extending from the upper end of the member 15 rearwardly to a rear wall 18 of the body 10. It will be noted that, since the attachment of the member 17 to the member 15 is substantially in the plane of the pins 16, flexing of the member 17 upon pivotal movement of the member 15 is reduced to a minimum.

The lower end of the pivoted member 15 carries a pile agitating member 20 of comb like characteristic which is adapted to comb out and disentangle from the fibers of a rug such surface litter as hairs and thread fibers and the like. By way of illustration the comb is shown in the form illustrated in the patent of Robert Lay Halllock, No. 2,377,778 issued June 5, 1945. The construction is such that, when the nozzle is moved forwardly over the rug and the pivoted member 15 swings rearwardly to abut the stops 19, the teeth of member 20 will be in operative rug contacting position as shown in Fig. 4 and the width of the suction opening 14 will be at its maximum.

The member 15 also carries a second and differently characterized rug agitator here shown in the form of a brush 21 which is mounted on the member 15 behind the comb 20. Rearward movement of the nozzle rocks the member 15 forwardly so that the comb is raised from the pile surface while the brush 21 is moved into contact with the pile to agitate it and to successively separate bristles of the rug so as to expose the bases thereof to the suction action. It will also be noted that such rearward movement of the nozzle brings the lower portion of the member 15 forwardly to a point where such said forward movement is stopped by members 22 which are so spaced with respect to the front lip 17 as to permit only a narrow air passage between the member 15 and the lip 13 so that air passing through the nozzle during the rearward stroke will have a considerable higher velocity than that admitted during the forward stroke when the pivoted member 15 is in the rear position and the suction opening 14 is at its maximum. It will be noted that during the rearward stroke the high velocity suction will act to take up such surface litter as the comb 20 has dislodged from enmeshment with the pile fabric as well as subjecting the rug pile to the high velocity suction action.

It will be understood, of course, that the arrangement of the agitators may be changed from the specific disclosure here made and thus the brush may be positioned to act with the comb in the forward stroke of the nozzle in addition to its action on the rearward stroke. It will also be understood that various other changes, modifications and the full use of equivalents may be resorted to without departure from the spirit or scope of the present invention and thus the type of rug agitators carried by the pivotally mounted member 15 may vary in accordance with the election of the designer or inventor to meet specific requirements.

What I claim is:

1. In a vacuum cleaner tool, a body having an elongated top surface apertured to permit the passage of air therethrough, fixed front and transverse walls depending from said top surface, said front wall terminating at its lower edge in a surface engaging lip, a fixed depending rear wall portion terminating in an edge substantially

above the horizontal plane of said surface engaging lip, a rear wall portion pivotally mounted on said transverse walls at a point intermediate the front wall and the terminal edge of the fixed rear wall portion and spaced from said terminal edge, said pivotally mounted rear wall portion depending to substantially the plane of said surface engaging lip, and a substantially horizontally disposed flexible wall joining said pivotally mounted and said fixed rear wall portions.

2. In a vacuum cleaner tool, a body having an elongated top surface apertured to permit the passage of air therethrough, fixed front and transverse walls depending from said top surface, said front wall terminating at its lower edge in a surface engaging lip, a fixed depending rear wall portion terminating in an edge substantially above the horizontal plane of said surface engaging lip, a rear wall portion pivotally mounted on said transverse walls at a point intermediate the front wall and the terminal edge of the fixed rear wall portion and spaced from said terminal edge, said pivotally mounted rear wall portion depending to substantially the plane of said surface engaging lip, and a substantially horizontally disposed flexible wall joining said pivotally mounted and said fixed rear wall portions, said pivotally mounted rear wall portion being provided with dissimilar agitating elements selectively engageable with a surface being cleaned in response to the direction of movement of the tool with respect to such surface.

3. In a vacuum cleaner, a body having a normally horizontal elongated top surface apertured to permit the passage of air therethrough, fixed front and transverse walls depending from said top surface, said front wall terminating at its lower edge in a surface engaging lip, a fixed depending rear wall portion terminating in an edge substantially above the horizontal plane of said surface engaging lip, a rear wall portion pivotally mounted on said transverse walls at a point intermediate the front wall and the terminal edge of the fixed rear wall portion and in a substantially common horizontal plane with and spaced from said terminal edge, said pivotally mounted rear wall portion depending to substantially the plane of said surface engaging lip, and a substantially horizontally disposed flexible wall joining said pivotally mounted and said fixed rear wall portions, said pivotally mounted rear wall portion being provided with dissimilar agitating elements selectively engageable with a surface being cleaned in response to the direction of movement of the tool with respect to said surface, and stop means on said body limiting movement of said pivotally mounted rear wall portion in both directions.
